UNITED STATES PATENT OFFICE.

ALONZO A. WARNER, OF NEW BRITAIN, CONNECTICUT, ASSIGNOR TO LANDERS, FRARY AND CLARK, OF NEW BRITAIN, CONNECTICUT, A CORPORATION.

SAFETY-RAZOR.

1,012,039.

Specification of Letters Patent. Patented Dec. 19, 1911.

Application filed December 15, 1910. Serial No. 597,474.

To all whom it may concern:

Be it known that I, ALONZO A. WARNER, a citizen of the United States, residing at New Britain, in the county of Hartford and State of Connecticut, have invented certain new and useful Improvements in Safety-Razors, of which the following is a specification.

My invention relates to improvements in safety razors, and the objects of my improvements are simplicity and economy in construction and convenience and efficiency in use, particularly with reference to holding a thin blade to the seat.

In the accompanying drawing: Figure 1 is a face view of my razor. Fig. 2 is an enlarged sectional view of the same on the line $\alpha\alpha$ of Fig. 1, a portion of the handle being broken away. Fig. 3 is a face view 20 of the frame on the same scale as Fig. 1, the blade and side plate being removed, and a portion of the handle broken away. Fig. 4 is a sectional view of the frame on the line $\gamma\gamma$ of Fig. 3. Fig. 5 is a plan view 25 of the blade. Fig. 6 is a plan view of the side plate. Fig. 7 is a plan view of the blank from which the frame is formed. Fig. 8 is a face view of my razor in a modified form, a portion of the handle being 30 broken away, and Fig. 9 is an enlarged end view of the same.

The frame of my razor comprises a back or seat 10 for one broad side of the blade, a longitudinal seat or stop 11 for the back 35 edge of the blade, spring clamps 12 and a toothed guard 13. The blade seat 10 is provided with a projecting shoulder 14, which may be formed by making a straight slit in the metal in the line of the said shoulder and 40 then bending a portion of the metal toward the front, so that the said shoulder projects from the face of the blade seat 10, as best shown in Fig. 2. An ordinary handle 15 is rigidly secured to this frame in the usual 45 position and in any ordinary manner. The said frame is formed by cutting a blank from sheet metal of the form shown in Fig. 7, the teeth of the guard 13 being cut from the edge of an opening or openings in the 50 body of the blank, leaving the guard in the form of a toothed bar, the said bar being connected with the back or body of the frame by bars 16, that are bent along the line of the ends of the teeth so that the 55 guard stands at the proper angle with the

ends of the teeth toward the blade, the said bars in effect also constituting guard teeth the ends of which are at the said bend, as shown in Fig. 2. The longitudinal seat 11 for the back edge of the blade is formed by 60 turning up that edge of the blank Fig. 7, which is opposite the guard teeth. The spring clamps or clamping mechanism 12 are formed by being bent over from the corresponding lugs of the blank, with their 65 ends inclined a little toward the blade seat 10, as shown in Fig. 4 so that their ends may yield and exert a pressure toward the blade seat when under tension.

The blade 17 is merely a flat thin piece, 70 with one edge sharpened and with an opening 18 near its back edge, the said opening having a straight edge on one side in position for engaging the shoulder 14 of the frame, to hold the blade against moving toward the front, while the back edge of the blade is stopped from moving in the opposite direction by the longitudinal seat or stop 11. The blade is inserted by introducing its cutting edge under the spring 75 clamps from the back and carrying the blade forward until seated as before described. It is then held firmly to its seat by crowding in the sliding clamp plate 19, between the broad side of the blade and the said 80 spring clamps from the back, until the end lugs 20 of the said plate engage the bent over portion at the junction of the said clamps with the blade seat 10, as shown in Fig. 1. The said bent over portion of the 85 spring clamps also hold the blade against endwise displacement.

In Figs. 8 and 9, I show the same general combination of frame, blade and clamping slide plate, only the parts are so modified 90 that the blade and slide plate must be inserted from the front instead of from the rear or back. The blade and slide plate are precisely the same as before described and hence the same reference numerals. The frame is 100 also provided with the same shoulder 14 for engaging the straight wall of the opening in the blade, a blade seat 10 for the broad side of the blade, spring clamps 12^a, for holding the slide plate, the same being bent 105 over from the back edge of the frame and forming a longitudinal seat 11^a for the back of the blade. The guard 13^a has its teeth formed on the outer edge of the blank and without the flat bar in the plane of the 110

teeth that is shown in the first described construction. The frame is also provided with short end lugs 21 to hold the blade against endwise movement and to serve as stops for 5 the lugs of the slide plate.

In both constructions the frame is provided with spring clamping mechanism which is put under tension by crowding the slide plate edgewise into place. In both, 10 the clamping mechanism holds the broad side of the blade to its seat while the frame is provided with means for preventing an edgewise displacement of the blade. The end lugs on the slide plate serve as convenient handles, in addition to their stop 15 function.

By my improvement the parts are formed mainly of sheet metal of a simple and inexpensive construction. The blade is conveniently put in place and when in place is firmly held to its seat by a clamping plate that may be thicker than the blade which may be quite thin. The guard teeth, with the exception of those formed by the connecting 20 bars, are straight and are in the plane of the straight flat bar that forms one edge of the frame, whereby they are less liable to injury, while the lather that passes by the said bar and teeth, readily passes 25 through the opening or openings in the frame from which the said teeth were cut.

I claim as my invention:—

1. In a safety razor, the combination of a flat thin blade, a frame comprising a back 35 provided with a seat for the broad side of the said blade, means for holding the said blade against edgewise displacement on the said seat, spring clamps consisting of extensions from said back to a position opposite 40 site the said blade seat and a slide plate

between the said blade and clamps, whereby the said clamps are put under tension by the act of positioning the said slide plate.

2. In a safety razor, the combination of a flat thin blade, a slide plate, and a frame 45 comprising a seat for the broad side of the blade, a pair of spring clamps at the opposite ends of the said frame, and means for holding the said blade against edgewise displacement, the said slide plate being forced 50 edgewise between one broad side of the plate and said pair of clamps.

3. In a safety razor, the combination of a flat thin blade, a frame comprising a seat for the broad side of the said blade, means 55 for holding the said blade against edgewise displacement and spring clamps, and a slide plate having lugs projecting from its opposite ends while its body between the said lugs may be forced in between the said blade and spring clamps to put said clamps under tension for holding the blade to its seat.

4. In a safety razor, a flat thin blade having an opening therethrough, a slide plate, and a frame comprising a guard near one 65 edge, a seat for one broad side of the said blade, a longitudinal seat at the back of the said frame for the back edge of the blade, a shoulder projecting from the said broad seat for being engaged by the rear wall of 70 the opening in the said blade, means for preventing an endwise movement of the blade on its seat, and spring clamps that may be put under tension by forcing the said slide plate edgewise into place.

ALONZO A. WARNER.
